Primary Examiner — Stacia Cadmus(74) *Attorney, Agent, or Firm* — Fay Sharpe LLP(57) **CLAIM**

The ornamental design for a tire tread, as shown and described.

DESCRIPTION

FIG. 1 is a perspective view of the tire tread of the present application;

FIG. 2 is a side view (first side) thereof;

FIG. 3 is a side view (second side) thereof;

FIG. 4 is a front view thereof; and,

FIG. 5 is an enlarged partial front view thereof.

The broken line showings of the sidewall, inner bead, and the peripheral boundary between the tire tread and the sidewall, and the text in FIG. 5, are included for the purpose of illustrating environment and form no part of the claim.
